UNITED STATES PATENT OFFICE

95,078

DESIGN FOR A STUDIO COUCH

Anthony J. Schob, Parkwood Manor, Pa.

Application January 14, 1935, Serial No. 54,854.

Term of patent 3½ years

To all whom it may concern:

Be it known that I, Anthony J. Schob, a citizen of the United States, and a resident of Parkwood Manor, county of Delaware, State of Pennsylvania, have invented a new, original, and ornamental Design for a Studio Couch, of which the following is a specification, reference being had to the accompanying drawing, forming a part thereof, wherein:

The figure is a perspective view of the studio couch showing my design.

I claim:

The ornamental design for a studio couch as shown.

ANTHONY J. SCHOB.
